TURNSTILE

Robert H. Ensign, Bronxville, N.Y., assignor to Perey
Manufacturing Co., Inc., New York, N.Y., a corpora-
tion of New York

Filed Mar. 5, 1968, Ser. No. 10,583

Term of patent 14 years

(Cl. D28—1)

FIG. 1

FIG. 2

FIG. 3

FIG. 4

FIG. 5

FIGURE 1 is a perspective view of the turnstile embodying my design as viewed from the front and to the left of the center thereof.

FIGURE 2 is a perspective view of the turnstile shown in FIGURE 1 as viewed from the rear and to the right of the center thereof.

FIGURE 3 is a rear elevational view of the turnstile shown in FIGURES 1 and 2.

FIGURE 4 is a front elevational view of the turnstile shown in FIGURES 1 and 2.

FIGURE 5 is a plan view of the turnstile.

The dominant features of the design are shown in full lines.

I claim:

The ornamental design for a turnstile, as shown and described.
